UNITED STATES PATENT OFFICE

2,278,353

ROD STRAIGHTENER.

Charlie A. Johnson, Dutton, Mont.

Application March 27, 1941, Serial No. 385,533

2 Claims. (Cl. 153—48)

My invention relates to improvements in means for straightening metal rods, shafts, and similar elements of farm machinery and the like, without disassembling the machinery, and the primary object of my invention is to provide simple, efficient, and inexpensive means of this character.

Other important objects and advantages of my invention will appear in the following description and the appended drawings, wherein for illustrative purposes, a preferred embodiment of my invention is shown.

In the drawings:

Figure 1 is a general fragmentary elevational view of a rod weeder showing the device of the invention applied to straighten one of the rods thereof.

Figure 2 is a top plan view of the device showing a portion of a rod therein.

Figure 3 is an enlarged end elevational view of the device partly broken away to disclose the adjustment slot.

Figure 4 is an enlarged fragmentary vertical sectional view taken through the pressure block.

Figure 5 is a fragmentary view similar to Figure 3 but showing adaptation of the device for straightening a square rather than a round rod or shaft.

Figure 6 is a perspective view of one of the square rod adapters for use with the device.

Referring in detail to the drawings, the device as a whole is designated 5 and consists of a pair of elongated parallel angle forms 6 and 7, respectively, which are spaced and connected by base plates 8 and 9, respectively, engaging the bottom of the horizontal flanges of the angle forms adjacent their opposite ends. The horizontal flange of the angle form 6 is riveted at 10 and 11 to the corresponding base plates 8 and 9, while the horizontal flange of the angle form 7 is slidably mounted on the base plates, the opposite ends of the horizontal flange of the angle form 7 having clamping bolts 12 and 13, respectively, depending therefrom through transversely elongated slots 14 and 15, respectively, formed in the corresponding base plates. This arrangement permits adjusting and locking the angle form 7 toward and away from the angle form 6 to accommodate rods or shafts of different diameters.

Rising along the outer side of the vertical flange of the angle form 6 near the middle thereof is a plate like standard 16 formed near its upper end with a pintle receiving hole or journal to receive the pintle on the adjacent end of the nut 17

which has its opposite pintle journaled in a similar hole in the upper hinged section 18 of the standard 19 which is secured to the outer side of the vertical flange of the adjustable angle form

5 1. Rivets 20 and 21 having heads flush with the inner surfaces of the said vertical flanges secure the standards 16 and 19 in place.

The horizontal axis hinge 22 secures the lower end of the standard section 18 to the upper end of the stationary portion 19. Cotter keys or the like 23 pass through the pintles 24 of the nut 17 outside of the standards to assemble the nut and the standards and mount the pressure screw 25 which threads through a diametrical bore in the nut 17 and has on its upper end a turning eye 26 and on its lower end a pressure block 27.

The lower end of the pressure screw has a reduced smooth round portion 28 having a smooth flange 29 on its lower end, the latter turning in the lower end of the bore 30 formed through the top of the rectangular body 31, with a split locking washer 32 entering the bore 30 through a slot 33 over the flange 29 to lock the block 27 rotatably on the lower end of the pressure screw.

20 25 The bottom of the block is formed with a wide longitudinal inverted V-shaped groove 34 to accept the top of the round rod or shaft 35 as in Figure 3 of the drawings or a narrow V-shaped groove 34' to accept the upper corner of the square rod 35'. When operating upon a square rod a hairpin shaped adapter 36 is utilized with its legs 37 placed along opposite sides of the square rod in the space between the slanted sides of the rod and the surface of the base plates 8 and 9 to prevent turning or rocking of the square rod.

30 35 To operate the present device, as in straightening the round rod 35 on the weeder 38, the screw 25 is swung on the axis of the pintles 24 to an out of the way position from that shown and the angle forms 6 and 7 brought up on opposite sides of the bend in the rod 35 so that the base plates 8 and 9 are on opposite sides of the bend and are at the concave side of the bend. The screw is then swung toward vertical position to apply the pressure block 27 to the middle of the convexity of the bend, and the screw being properly turned to move toward the bend, is further turned to put extreme pressure on the block 27 by turning the eye 26 with a suitable lever, until the bend in the rod 35 or 35' has been straightened out to the extent desired. The screw 25 is then backed off and when free is swung out of the way and the angle forms 8 and 9 removed from the straightened rod or shaft. Sufficient play is provided in the component parts of the

device to accommodate lateral adjustment of the angle form 7 without disaligning the parts, the hinge 22 allowing for sufficient displacement of the hinged section 18 when a wide adjustment of the angle form 7 is made.

Removable pins 39 and 40, spaced on opposite sides of the pressure assembly and traversing the vertical flanges of the angle forms 6 and 7 may be provided as rests for short lengths of rod or shaft to be straightened.

Although I have shown and described herein a preferred embodiment of my invention, it is to be understood that I do not wish to limit the application of my invention thereto, except as required by the scope of the subjoined claims.

Having described the invention, what is claimed as new is:

1. A device for straightening bent rods and the like comprising a base including a pair of laterally spaced horizontal bars for accommodating a rod therebetween, a pair of opposed standards arising from said base, a rocker member journaled at its ends in said standards to extend transversely of the bars and above the same, an upright screw shaft threaded downwardly through said member for endwise adjustment into and out of the space between said bars and for swinging lengthwise of said space under rocking of said member, and a pressure block in which the lower end of the shaft is rotatably secured, said block slidably fitting between said bars against turning whereby said block is ad-

justable vertically under adjustment of said shaft and swingable in said space in opposite directions under swinging of said shaft, one of said bars being adjustable laterally to vary the width of said space, and one of the standards having a lower hinged section permitting such adjustment of said one bar.

2. A device for straightening bent rods and the like comprising a base including a pair of laterally spaced horizontal bars for accommodating a rod therebetween, a pair of opposed standards arising from said base, a rocker member journaled at its ends in said standards to extend transversely of the bars and above the same, an upright screw shaft threaded downwardly through said member for endwise adjustment into and out of the space between said bars and for swinging lengthwise of said space under rocking of said member, a pressure block in which the lower end of the shaft is rotatably secured, said block slidably fitting between said bars against turning whereby said block is adjustable vertically under adjustment of said shaft and swingable in said space in opposite directions under swinging of said shaft, one of said bars being adjustable laterally to vary the width of said space, and one of the standards having a lower hinged section permitting such adjustment of said one bar, and a forked adapter fitting lengthwise in said space for supporting a transversely square rod with one edge uppermost.

CHARLIE A. JOHNSON.
